COATING MATERIAL SPRAYING APPARATUS

Alexander M. Fleming, Grosse Pointe, Mich., assignor to Chrysler Corporation, Highland Park, Mich., a corporation of Delaware

Application October 7, 1938, Serial No. 233,704

7 Claims. (Cl. 91—45)

This invention relates to improvements in paint spraying devices.

More particularly, the invention pertains to the provision in paint spraying apparatus of mechanism by which coating materials of various colors or kinds may be selectively discharged from the same spray gun.

Difficulty is experienced in production painting of articles, such as automobile bodies, with paints of various colors, inasmuch as it is necessary to manually uncouple the spray discharge gun from a hose conveying paint of one color, clean the paint discharge passage of the gun and then couple the gun to a hose conveying paint of another color. This uncoupling and coupling of the spray gun to accommodate spraying of paint of various colors necessitates a loss of time, additional labor and a consequent slowing up of the production line schedule. In some instances, a plurality of spray guns are provided, each of which is continuously coupled with a hose for one of the more widely used colors, but this system entails a considerable investment in paint spray equipment.

One of the main objects of the invention is to overcome these difficulties by providing an improved surface coating material spraying apparatus which can be quickly conditioned to selectively discharge any one of a plurality of different coating materials from a single spray gun.

A further object of the invention is the provision in apparatus of this kind for flushing and cleaning of the spray gun and those passages of the apparatus through which differently colored coating materials flow, immediately before a change is made in the color of the coating material being discharged.

Another object of the invention is the provision of selective valve mechanism which has a single control member by which it may be conditioned to clean the spray gun and associated discharge passages of the apparatus and to discharge coating materials of different colors respectively.

A further object of the invention is the provision in valve mechanism of this kind of cleaning medium ports between each pair of successive coating material ports in order to accommodate conditioning of the valve mechanism for cleaning operations without requiring movement of the control member to or beyond the next successive coating material discharging position adjacent which it is disposed.

Additional objects of the invention are the

provision in selective valve mechanism of this kind of means, operable by the control member, for individually releasably obstructing the flow of coating material of each kind or color when not in use; to provide means of this kind which is so constructed and arranged as to prevent the application on the relatively movable parts of the selecting mechanism of the pressure of more than one of the different coating material pressure lines at any time; and to provide selective valve mechanism which, because of the relatively low pressure to which it is subjected, can be effectively and conveniently sealed against leakage without excessively raising the force required to effect manual selective adjustments thereof.

Other objects and advantages of the invention will be more apparent from the following description taken in connection with the accompanying drawings, in which:

Fig. 1 is a rear elevational view of a spraying apparatus valve mechanism embodying the invention, a portion of the casing thereof being broken away to show underlying structure.

Fig. 2 is a front elevational view of the spraying apparatus valve mechanism shown in Fig. 1 and showing the selector member at one of its stations.

Fig. 3 is an enlarged fragmentary sectional view taken as indicated by the line 3—3 of Fig. 1, and illustrating the manner in which a spray gun is connected with the improved selective valve mechanism.

Fig. 5 is an enlarged sectional view taken approximately as indicated by the line 4—4 of Fig. 1.

In the form of the invention illustrated in the drawings, the improved selective valve mechanism 10 is illustrated in connection with a paint spray apparatus although it is to be understood that this mechanism may be used to accomplish selective controlling of the passage of a plurality of different substances.

The valve mechanism 10 comprises a base 11 to which is detachably secured a dish-like mounting member 12 which has ten equi-distant radially extending passages 13 which communicate with each other at their origin, although any number of radial passages may be used. The plate 12 is provided with circumferentially arranged series of apertures 14, 15 and 16, the apertures 16 being located adjacent the periphery of the plate 12, the apertures 14 being located adjacent the base 11 and the apertures 15 (best

shown in Fig. 4) being disposed radially between the series of apertures 14 and 16.

Secured to the inner face of the dish-like member 12, as by screws 17, is a casing 18 to which is detachably secured a cover 19. The casing 18 has a central bore 20 and is provided with a series of weight-reducing recesses 21. The casing 18 further comprises a flange portion 22 having a series of axially extending coating and cleaning material valve chambers 23 and 23' respectively formed therein, each in alignment with one of the apertures 16 of the mounting member 12. The right-hand face of the casing 18 has an annular beveled valve seat 24 and an adjacent annular groove 25. Passages 26 extending through the casing 18 communicate at one end with the groove 25 and at their other ends with tubes 27 which project through the apertures 14 and are threaded in the left extremities of the passages 26. The outer extremities of the tubes 27 are closed by caps 28 which may be removed to accommodate draining of the groove 25 and passages 26. Formed in the flange 22 and adjacent portions of the casing 18 are a series of radially extending coating and cleaning material passages 29 and 29'. Each of the passages 29 opens through the valve seat 24 and extends to one of the coating material valve chambers 23 and each passage 29 also opens through the valve seat 24 and extends to one of the cleaning material valve chambers 23'. There are provided two coating material valve chambers 23 and associated passages 29 between each pair of cleaning material valve chambers 23' and associated passages 29' respectively.

Each cleaning material valve chamber 23' is communicatively connected with one of the radial passages 13 by a conduit 30, one of the conduits 30 being provided with an inlet branch 30' through which paint solvent such as paint thinner or the like is supplied to the device. Differently colored paints or different kinds of coating material may be fed to each valve chamber 33 by conduits 9 communicating with the interior thereof.

In each of the valve chambers 23 and 23' is a sleeve 31 having an aperture 32 registering with the passages 29 and 29' and in which valves 33 and 33' respectively are slidably mounted to control the aperture 32. Each of the valves 33 and 33' are slidably supported within the aperture 16 of the member 12. A spring 37 is interposed between an abutment 36 on each valve 33 and 33' and the member 12 to yieldingly urge the valves 33 and 33' to their closed positions. Suitable threaded sealing means such as those indicated at 39 may be employed to seal the ends of the valve chambers 33 and 33'.

To selectively control the passage of paint from the inner ends of the passages 29 and cleaning material from the inner ends of the passages 29', a rotary valve, generally designated by the numeral 45, is mounted adjacent the right side of the casing 18, as viewed in Fig. 3, between the latter and its cover 19. The valve 45 comprises spindle portions 46 and 46'. The spindle portion 46 is journaled in the bore 20 of the casing 18 and the spindle portion 46' is journaled in a bearing 54 mounted in the casing cover 19. The valve 45 further includes an annular beveled face 47 which seats on the valve seat 24 of the casing 18. Within the valve 45 a passage 48 which opens through the beveled face 47 extends to the extreme right end of the valve 45. The inner end of the passage 48 is adapted to regis-

ter with inner ends of the passages 29 and 29' and is communicatively connected with a spray discharge device 85 by a flexible hose 86. A suitable sealing member such as a felt ring 49 is interposed between the valve 45 and the casing 18 to prevent fluid escaping inwardly from the groove 25.

The cover 19 has an annular groove 55 in its inner side which receives any leakage of fluid escaping from the valve seat 24, the fluid from the seat being drained or pumped through passages such as a passage 58 (best shown in Fig. 4) and through a capped threaded tube 57 extending through the aperture 15 of the member 12. The cover 19 further includes an annular groove 58 from which extend a series of circumferentially spaced recesses 59. Mounted in the groove 58 is a thrust bearing unit 63 which is urged against the valve 45 by springs 61 and plungers 62 disposed in the recesses 59. The springs 61 bear between the plungers and an abutment 60 which is adapted to be adjustably positioned by a set screw 64. An annular sealing ring 65 is interposed between the cover 19 and the valve 45 to prevent the fluid within the groove 55 from escaping inwardly to come in contact with the bearing unit 63 and the surrounding mechanism. Fixed to the rightwardly face of the cover 19, as viewed in Fig. 3, is an annular ring 66 having indicia 67 as shown in Fig. 2 to indicate to the operator whether that position is to admit paint solvent into the valve passage 48 or whether it is to admit a certain color of paint.

Any suitable selective control member is provided to rotate the valve 45 and to open one of the individual valves 33 at a time such as the control member generally indicated by the numeral 70. This control member 70 comprises an arm 71 having a split end portion 72 which is non-rotatably and detachably secured to the external end of the spindle portion 46' of the valve 45. The arm 71 has a central opening 73 which is adapted to register with the indicia 67 during rotation of the arm 71 to permit observation thereof by the operator when the mechanism is set at its various stations. An index finger member 74, preferably secured to the arm 71, registers with the indicia 67. The arm 71 has a head on its free extremity in which is provided a bore 76 for receiving a plunger 81 which is normally urged rightwardly, as viewed in Fig. 3, by a spring 81'. The left end of the plunger 81 is adapted to register with the right extremities of the valves 33 and 33'. An operating lever 77 is pivotally mounted intermediate its ends at 79 on a pair of spaced flanges 75 extending rightwardly from the head of the arm 71 as illustrated in Fig. 3.

The extremity of the end portion 80 of the lever 77 is adapted to engage and urge the plunger 81 leftwardly when the lever 77 is turned in a clockwise direction from its dotted line position 82 to its full line position, as viewed in Fig. 3. When the handle 77 is swung outwardly to a position indicated at 82 in Fig. 3, the plunger 81 is spring-urged away from the end portion of the valve 33 or 33' with which it registers, thereby urging the valve 33 to its closed condition by the spring 37. When the lever 77 is in this position, it may be rotated together with the valve 45 about the axis of the latter to bring the plunger 81 into registration with any of the valves 33 and 33' and, as this is done, the outer end of the passage 48 is brought into communication with the passage 29 or 29' corresponding to the

valve 33 or 33' with which the plunger 81 has been registered.

Referring to the operation of the illustrated embodiment of the invention, when the operator rotates the valve 45 so that the index finger 74 registers with a desired coating material color indicia, the rotary valve passage 48 is in communication with a corresponding passage 29 of the casing 18. Thereupon the operator swings the handle 77 to its full line position shown in Fig. 3 so that the engaging end portion 80 of the handle 77 moves the plunger 81 to open the corresponding selected valve 33 to admit a selected color of coating material to the passage 48 from which it is supplied to the spraying apparatus. When the operator desires to change to another color of paint, he swings the handle 77 to its position of 82 in Fig. 3 so that the spring 37 may urge the valve 33 to its closed position to stop the flow of paint to the valve 45. He then preferably rotates the arm 71 until the index finger 74 registers with one of the paint remover or thinner indicia, and then moves the handle 77 to its full line position of Fig. 3 so that one of the thinner valves 33' is opened to discharge paint thinner or the like through the common valve passage 48 and through the passages of the spray gun apparatus 85. At the same time, the operator opens the valve in the spray gun 85 to spray out the paint and the paint thinner within the passage 48, hose 86 and paint discharge passage of the spray gun so as to thoroughly clean and flush out such passages after coating material of one color has been sprayed and before spraying of coating material of another color. Next, he rotates the arm 71 until the index finger registers with the next color of paint desired, and this rotates the valve 45 to the proper position to accommodate the passage of the newly selected color of paint. Then the operator swings the handle 77 to its position of Fig. 3 so that the proper paint valve 33 is opened to admit the selected paint through the proper paint passages 29 to the valve passage 48.

The improved spraying apparatus quickly accommodates selective passage of paint of various colors to a single spray discharge device and by providing a cleaning material outlet port on each side of each pair of coating material ports, the operator is required to move the control member a distance of only one station to condition the device for flushing and cleaning between spraying of different colors of material. This is particularly advantageous in production painting of automobile bodies, for example, inasmuch as one operator can conveniently paint vehicle bodies with paints of different colors with a single spray gun without requiring coupling and uncoupling of individual hoses which supply the various paints. This effects a substantial saving in time and labor, particularly since the improved spraying apparatus accommodates efficient cleaning of the common spray passages between selection of paints. By reason of the aforesigned advantages, the improved apparatus is readily adaptable for controlling the passage of paints of different colors or kinds to automatic or semi-automatic paint spraying apparatus.

The improved spraying apparatus is very compact and efficient, and is so arranged that the master selector valve 45 is not subjected to the pressure of more than one of the paint lines. Consequently, the effort required to rotate the

valve 45 is very slight and it is possible to have a satisfactory sealed spray apparatus.

Although but one specific embodiment of the invention is herein shown and described, it will be understood that various changes in the size, shape and arrangement of parts may be made without departing from the spirit of the invention.

I claim:

1. Selective valve mechanism for controlling the discharge of a plurality of different fluids comprising a casing having a body portion provided with a plurality of passages each having an inner end opening in said casing, a movable valve element in said casing having a valve seat for closing the inner ends of said passages and having a passage therein comprising an inner open extremity adapted for selective communication with the passages of said body portion and an external end portion for conveying fluid from said casing, a valve in each of said passages for normally closing the latter in advance of said valve seat, a combined handle and control element for moving said valve element and opening the valves of the passages of said body portion respectively, said handle and control element being so constructed and arranged with respect to the inner open extremity of the passage in said movable valve element as to operate upon only the valve of that passage of said body portion which is in communication with the passage of said movable valve element.

2. In coating material spraying mechanism including a spray gun and sources of coating and cleaning materials under pressure; mechanism for selectively supplying differently colored coating materials and cleaning material to said gun comprising a casing having a body portion provided with a plurality of passages for conveying differently colored coating materials and a passage for conveying a cleaning material, means for supplying coating and cleaning materials to said passages respectively, a movable element in said casing having a passage selectively communicatively connectable at one end with each of said passages of said body portion, a valve in each of said passages normally closing the same in advance of said movable element, means for connecting the other end of said passage to said spray gun, and a control member operatively connected with said movable element for selectively bringing the passage of the latter into communication with any of said body portion passages, said control member including a manually operable valve selecting and opening lever portion and a valve opening element operable thereby so constructed and arranged with respect to the passage of said movable element that said valve opening element registers with and is adapted to open only the valve of said body portion passage which is in communication with said passage of said movable member.

3. In coating material spraying mechanism including a spray gun; mechanism for selectively supplying differently colored coating materials and cleaning material to said gun comprising a casing having a body portion provided with a plurality of circumferentially spaced pairs of passages for conveying differently colored coating materials and having a cleaning material passage between each pair of coating material passages, means for supplying coating and cleaning materials to said passages respectively, a valve in each of said passages normally closing the same, a movable valve element rotatably

mounted in said casing having a passage selectively connectable at one end with each of said body portion passages respectively and adapted in all positions of said element to be brought into communication with a cleaning medium passage by rotation of said element from only one of its stations to an adjacent station, a control member operatively connected with said movable valve element for selectively positioning the latter to bring its passage into communication with any of said body portion passages, said control member including means for opening the valve of that passage of said body portion with which the passage of said movable valve element is connected.

4. In coating material spraying mechanism including a spray gun; mechanism for selectively supplying a plurality of differently colored coating materials to said gun including a casing having an annular valve seat therein and a plurality of passages having circumferentially spaced open ends in the plane of said valve seat, means for supplying differently colored coating materials to said passages under pressure, a movable element in said casing having a valve seat in sealing engagement with the valve seat of said casing and having a passage provided with an open end in the plane of its valve seat, the open end of said movable element passage being selectively registerable with the open ends of said casing passages, a valve for normally closing the passages of said casing in advance of and relieving said valve seats of the pressure of the coating material therein, and valve opening mechanism including a member carried by said movable element and so constructed and arranged as to operate upon the valve of that passage of said casing with which the valve of said movable element is registered.

5. Selective valve mechanism including a casing having a body portion provided with a plurality of inlet passages, a valve in each passage normally closing the latter, a movable element in said casing having an outlet passage selectively registerable with a portion of each of said inlet passages on the discharge side of the valve thereof, and means for moving said element for selectively bringing said outlet passage into communication with each of said inlet passages respectively including a valve opening element for operating upon only the valve of that inlet passage which is in communication with said outlet passage at any setting of said element.

6. In coating material spraying apparatus in-

cluding a spray gun; mechanism for selectively supplying a plurality of different coating materials and a cleaning material to said gun including a member having a plurality of passages for conveying differently colored coating materials and a cleaning fluid under pressure, a second member movable relative to said first member having a passage therein connected with said spray gun and selectively communicatively registerable with said passages of said first member, a valve in each of said first mentioned passages for closing the latter in advance of said second member, means for producing relative movement between said members to initially selectively bring the passage of said second member into communication with one of the passages of said first member, and mechanism operable by said means for opening the valve of the passage of said first member which is in communicative relation to the passage of said second member.

7. Selective valve mechanism for fluid material spraying apparatus including a body member having a plurality of inlet passages therein for receiving different kinds of fluid material, said body member having a valve seat common to the outlet ends of all of said inlet passages, an individual valve in each of said outlet passages in advance of said valve seat for normally closing the latter, a valve member adjacent said body member having a surface engaging said valve seat and having an outlet passage therein adapted for selective communication with the passages of said body member, said body and valve members being relatively movable for selectively bringing the passages thereof into communicative relationship, valve opening mechanism including an operating element mounted on said valve member for selectively registering with the individual valves in said outlet passages of said body member after predetermined relative movement of said body and valve members and adapted to open the valves of said outlet passages, said operating member and the outlet passage of said valve member being so constructed and arranged with respect to each other that when in any one of its positions said operating member registers with and is adapted to open the individual valve of that passage of said body member which is disposed in communication with the passage of said valve member, and means for supplying different fluid material compositions to each of said inlet passages respectively.

ALEXANDER M. FLEMING.
